UNITED STATES PATENT OFFICE

2,523,755

STENOGRAPHIC COPYHOLDER

Samuel Ford and Robert B. Warner, Los Angeles, Calif., assignors to Ford-Warner Manufacturing Company, a corporation of Nevada

Application November 29, 1948, Serial No. 62,526

1 Claim. (Cl. 120—34)

1

This invention relates to a stenographers' copy holder, more particularly of the type illustrated in applicants' co-pending application, Serial No. 52,566 and has for its principal object the provision of a simple and highly efficient device upon which a typewriter may be placed, and which can be adjusted to hold the matter being copied above the typewriter and within convenient view of the operator, and which will provide a key alongside the keyboard of the typewriter which will operate a copy indicating device upon the copy holder.

Another object of the invention is to so construct the device that it will be adjustable to different makes of typewriters and to the personal needs of the stenographers.

Other objects are: to provide a copy holder which can be extended to support unusually wide sheets of copy material; to provide a copy holder which can be quickly and easily dismantled and assembled, and which can be folded down upon the typewriter to allow the latter to be covered or lowered into a desk.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 illustrates the improved copy holder assembled ready for use;

Fig. 2 is a side view thereof, illustrating the position of a conventional typewriter thereon;

Fig. 3 is a rear view thereof;

Fig. 4 is a detail, fragmentary, front view of a portion of a copy-holding bar employed in the improved holder;

Fig. 5 is a similar detail view, illustrating a side view of the bar of Fig. 4;

Fig. 6 is a similar view, illustrating the holding bar in the release position;

Fig. 7 is a fragmentary, enlarged, front view of a portion of the holder, taken on the line 7—7, Fig. 2;

Fig. 8 is a detail section, taken on the line 8—8, Fig. 7;

Fig. 9 is a similar section, taken on the line 9—9, Fig. 8;

Fig. 10 is a still further enlarged side view of an operating lever employed in the device;

Fig. 11 is a horizontal section, taken on the line 11—11, Fig. 10; and

Fig. 12 is a detail view of an extension line indicating device used in connection with the improved holder.

The improved copy holder is mounted on a base

plate 12 having upturned side and back flanges 13. The base plate 12 is of a size to receive the four supporting legs of a standard typewriter, such as indicated in broken line at 14 in Fig. 2. A supporting frame 15 is riveted or otherwise secured at the rear of the base plate 12 through the medium of attachment feet 16. The frame 15 and the base plate 12 are rigidly secured together at right angles to each other so that the frame 15 will stand upright parallel to the back of the typewriter 14.

The frame 15 is provided with two vertical channel members 17 designed to slidably receive supporting bars 18 and 19. The bars 18 and 19 may be secured at any desired height in their channel members 17 by means of set screws 20. The upper extremities of these two bars are bifurcated to receive bracket ears 21, and are provided with bolts and nuts 22 for clamping the furcations together against the ears 21.

The ears are fixedly mounted on, and extend downwardly from, a copy-supporting ledge 23 formed on a back plate 24. The material to be copied is supported on the face of the back plate 24 by means of a horizontally extending clamping bar 25. The bar 25 is supported across the top of the plate 20 on two end arms 26 which are bent to extend upwardly over the upper edge of the backing plate 24, thence forwardly and downwardly to pivot clips 27 on back of the plate 24. The end arms 26 curve upwardly above the plate 24 to allow paper sheets to extend beyond the sides of the backing plate and to be removed from the sides of the plate without interference from the arms 26.

A line guide shaft 28 extends across the front of the plate 24 from a sliding bracket member 29. A line guide member 30 is hingedly mounted on the shaft 28 so that its upper edge may lie against the plate 24. The free extremity of the shaft 28 is supported from the plate 24 on a freely rotating roller 31.

The sliding bracket member 29 is secured to a carriage 32 which engages the back of the plate 24 to hold the bracket member 29 in slidable engagement therewith. The carriage supports a shaft screw 33 upon which a roller 34 is mounted. The roller 34 is grooved to roll along a fixed guide rod 35 mounted vertically on the back of the backing plate 24.

A clutch-arm 36 is swingingly mounted on the shaft screw 33. A push rod 37 passes through an opening in the clutch arm 36, and the latter is forced downwardly by means of a leaf spring 38 so that the opening will clamp the push rod. Each downward movement of the rod 37 therefore carries the carriage 32 and the line guide member 30 downwardly. Each upward movement of the rod 37 simply lifts the clutch arm 36 so that the rod 37 will freely pass through the latter so as not to im-

60

part upward movement to the line guide member.

The entire guide assembly is yieldably supported in any desired position by means of a braking spring 39. The braking spring 39 constantly bears against the roller 34 to resist rotation in either direction. The entire mechanism on the shaft screw 33 is enclosed in a suitable case or housing 40.

The push rod 37 is constantly urged upwardly by means of a tension spring 41, by means of which the rod is suspended from the upper edge of the plate 24. The lower extremity of the push rod 37 is hingedly secured to an operating lever 42 which is pivoted to a bracket 43 upon a pivot screw 44. The bracket 43 is riveted or otherwise secured to the back of the plate 24 adjacent the lower right-hand corner thereof.

The downward arc of movement of the lever 42 is limited by means of a stop ledge 47 extending from the bracket member 43.

The amount of upward movement of the operating lever 42 can be adjusted to any desired line spacing by means of an adjusting screw 45, the lower extremity of which is in the path of the lever 42. Accidental rotation of the screw 45 is prevented by means of a rotation-resisting spring 46.

The lever 42 can be forced downwardly directly by hand, if desired. It is preferred, however, to place means more in convenient reach of the operator for operating this lever.

For remote operation, a flexible wire 48 extending through a flexible tube 49 is employed. The upper extremity of the wire is clamped in a terminal block 50 by means of a set screw 51. The extremity of the terminal block 50 is reduced to form a pivot shaft 52 which extends through a clip 53 in which it is secured by means of a cotter key 54. The clip 53 is mounted on the lever 42 by means of a mounting screw 55 which is threaded into the extremity of the lever 42.

The upper extremity of the flexible tube 49 is supported in a bracket 56 rigidly attached to, and extending from, the supporting bar 19. The lower extremity of the tube 49 is secured to one of the side flanges 13 by means of a clamp screw 57. The lower extremity of the wire 48 projects from the tube 49 and is secured to a pivot rivet 58 in a hand lever 59 mounted on a hinge bolt 60 in the side flange 13.

The lever 59 carries a finger button 61 in its forward extremity which, when the typewriter 14 is in place, is positioned at the right side of the keyboard of the typewriter.

In use, the typewriter is placed on the base plate 12. The screws 20 are loosened and the bars 18 and 19 are raised and lowered to position the plate 24 at a convenient height for the particular stenographer. The set screws are then tightened and the copy is slipped beneath the clamping bar 25 and beneath the line guide member 30. The clutch arm 36 is lifted by squeezing it between the thumb and finger toward a fixed finger clip 62. This releases the line guide, which is moved to the uppermost line of the copy and the adjusting screw 45 is adjusted for the line spacing on the copy.

Copying is then commenced. At the conclusion of each line of copy, the stenographer simply strikes the finger button 61, which causes the line guide member to move down a preset line space.

If unusually wide copy be encountered, a side extension plate, such as indicated at 63, can be

applied to the left side of the plate 24. The extension plate is provided with tenon members 64 which extend into openings in receiving clips 65 on the back of the plate 24, in which they may be locked by means of set screws 66.

The line guide member 30 may be extended over the extension plate 63 by means of an edge extension member 67, as shown in detail in Fig. 12. The extension member 67 is formed in a U-shape, which can be slipped over the upper edge of the line guide member 30, and is provided with a retaining spring 68 which snaps over the line guide shaft 28.

While a specific form of the improvement has been described and illustrated herein, it is to be understood that the same may be varied, within the scope of the appended claim, without departing from the spirit of the invention.

Having thus described the invention, what is claimed and desired secured by Letters Patent is:

Means for supporting and operating a copy-holder and a line indicating device over a typewriter comprising: a base plate adapted to support the typewriter; upturned side and back flanges along the side and back edges of said base plate; a vertical supporting frame secured to and arising from said base plate along the rear edge thereof; two vertical, spaced-apart channel members in said frame; a supporting bar vertically slidable in each channel member, each bar having a bifurcated upper extremity; a set screw in said frame engaging each bar to support the latter at any desired height in its channel member; a bracket ear hingedly mounted in the bifurcated upper extremity of each post; means for locking said bracket ears in said bifurcations; a copy supporting ledge member fixedly mounted on and extending between said bracket ears, said holder and said line indicating device being supported from said ledge member; a hinge bolt extending through one of the side flanges of said base member; a hand lever hingedly mounted on said hinge bolt and extending forwardly therefrom; a flexible member extending from said hand lever to said line indicating device for operating the latter; and a supporting arm mounted on one of said vertical bars and supporting said flexible member.

SAMUEL FORD.
ROBERT B. WARNER.
